TANK

Francisco de la Cuesta, Habana, Cuba

Application September 27, 1937, Serial No. 165,993

1 Claim. (Cl. 4—46)

This invention refers to tanks, especially to those used in water closets, either of upper or lower type, and the principal purpose of the invention is to provide means for avoiding the leakage of these tanks, caused by deficiency in the valves used at present.

In the drawings:

Figure 1 is a side elevation of a water closet tank of lower type equipped with the improvement subject of the present invention.

Figure 2 is an upper plan view of same.

Figure 3 is a vertical longitudinal partial sectional view in an enlarged scale as per line 3—3 of Figure 1.

Figure 4 is a front view, partially sectioned, of the tank.

Figures 5, 6 and 7 are perspective views, in detail, of the different parts of the invention.

Figure 8 is an upper plan view, in detail, of the tank; the floater being removed therefrom.

Figure 9 is a sectional longitudinal view as per line 9—9 of Figure 8.

Figure 10 is a sectional partial view as per line 10—10 of Figure 8.

Figure 11 is a side elevation, partially schematic, of the invention in connection with a tank of the upper type.

Figure 12 is an upper plan view of same.

Figure 13 is a front elevation, partially sectioned.

Making reference to these figures, 1 is a tank of a water closet of the lower type; the water being supplied as usual.

At the bottom of the tank there is an opening 35 where through a packing 2, a pipe 3 is secured thereto, which pipe, as shown in Figure 6, is enlarged in its upper end 3' which is closed, as shown by 3'' and near to same there are several slots 4. To the threaded end of the pipe 3 which 40 projects out of the tank is threaded the elbow of the discharging pipe 5 which leads to the bowl.

This pipe 3 has secured in its closed upper end a threaded stem 5 whereon, through a nut and washer 7, a cylindrical casing 8 is secured; 45 the lower part of this casing has a flanged edge 9 and a cylinder 10 forms an integral part of common wall with the casing 8, which cylinder is open in its upper part. This embodiment is placed in such a manner that the flanges 9 stand 50 on the bottom of the tank 3 forming a chamber 11, the walls of which have slots 12 closed by check valves 13 which open inwardly.

In the inner part of cylinder 10 a floating plunger 14 is placed and its rod 15 is guided 55 through a slot in the cross-head 16 which is

fastened to the upper edge of cylinder 10; the rod having two eyebolts 17 and 18 at its upper end. The lever 19, which forms part of the usual discharging system operated by handle 20, is engaged to the eyebolt 17.

The rod 21, of the inlet means to supply water to the tank, is engaged to the eyebolt 18.

In Figures 11, 12 and 13 the invention is shown in connection with a tank of the upper type and the only variation is that cylinder 8 has an ear 10 22, where rod 23, of the usual discharge engages, and said rod slides through the upper end of rod 15 standing in its opposite end on a forked bracket 24 fastened to one of the heads of tank 1.

In this embodiment no connection with the 15 water inlet means appears and it is made by the usual floater system, though this arrangement may be similar to the aforesaid explained for tanks of the lower type.

The operation takes place as follows:

Once the water fills the tank 1, it will have passed through the openings 12 and check valves 13 which open inwardly, and filling the chamber 9 below the casing 8 and cylinder 10 forcing the latter upward to plunger 14 until it is stopped by 25 the cross-head 16 and at that moment the inlet of the water is closed because plunger 14 works as a floater.

The overflow, if any, will discharge through 30 slots 4 of pipe 3.

By operating handle 20, in case of a tank of lower type, or by pulling the chain, in case of a tank of upper type, the plunger 14, as shown in dotted lines, of Figure 3, will be forced downward compressing the volume of water in cylinder 10 35 causing check valves 13 to remain closed and upon the rising of the liquid column through the annular chamber between pipes 3 and 8, and discharging through openings 4 of pipe 3, a 40 siphon flow will be formed causing the complete discharge of the tank through the elbow pipe 5 towards the bowl.

While the tank is filled a tight hydraulic sealing is supplied so that there is not the slightest leakage of water into the bowl.

I claim:

In a flush tank, a pipe fixed in an opening in the bottom of the tank and extending upwardly, a cylindrical casing having a closed top surrounding the pipe in a spaced relation with 50 respect thereto, a cylinder arranged adjacent said casing and having a wall portion formed integrally with a wall portion of the casing to provide a wall portion common to the cylinder and the casing, said common wall portion being 55

terminated at the lower end to provide a passage from the cylinder to the casing, a plurality of flap valves for admitting fluid from the tank to the lower portion of the cylinder and the casing, a floating piston arranged for reciprocation in the cylinder, an inlet pipe for said tank, a lever operably responsive to the upward movement of

said piston for closing said inlet and manually operable means for moving said piston downwardly in the cylinder to open said inlet whereby the fluid pressure closes said flap valves and discharges liquid through said pipe during the downward movement of said piston.

FRANCISCO DE LA CUESTA.
